FIG. 1

FIG. 2

FIG. 3

FIG. 4

FIG. 1 is a perspective view of a knife showing our new design.

FIG. 2 is a side elevational view thereof, the opposite side being a mirror image thereof.

FIG. 3 is a top view thereof.

FIG. 4 is a bottom view thereof.

The characteristic feature of our design resides in the combination on a knife of a V-shaped scalloped juncture portion between the blade and handle portion, said scalloped juncture line paralleling the configuration of the handle tip, a longitudinal ridge line extending from the apex of the scalloped juncture line to the handle tip all as shown.

We claim:

The ornamental design for a knife, as shown and described.
